UNITED STATES PATENT OFFICE.

RAYMOND G. MOORE AND ARTHUR CLAUD-MANTLE, OF BRIDGEPORT, CONNECTICUT,
ASSIGNORS TO THE BASSICK COMPANY, OF BRIDGEPORT, CONNECTICUT, A COR-
PORATION OF CONNECTICUT.

LATCH.

Application filed June 17, 1926. Serial No. 116,529.

The present invention relates to latches, particularly of the type adapted for use with kitchen cabinets or the like, and has for an object to provide a latch of this character which may be formed from sheet metal, and which will be very simple and inexpensive in construction and assembly, and efficient and reliable in operation.

It is particularly proposed to provide a latch having a spring actuated latch bolt, and a spring actuated operating handle adapted to be yieldably retained in its normal position independently of the position of the latch bolt.

A further object is to provide a latch which may be used with equal facility on either a right or left hand door.

Another object is to provide a construction in which the handle may, by simple adaptation methods, be made to operate either upon an axis at right angles to, or parallel to, the direction of movement of the latch bolt.

With the above and other objects in view, embodiments of our invention are shown in the accompanying drawings, and these embodiments will be hereinafter more fully described with reference thereto, and the invention will be finally pointed out in the claims.

In the drawings:—

Fig. 1 is a plan elevation of a latch, according to one embodiment of our invention;

Fig. 2 is a side elevation thereof;

Fig. 3 is a bottom plan view;

Fig. 4 is a longitudinal sectional view, taken along the line 4—4 of Fig. 1, and showing in dotted lines the retracting position of the handle and latch bolt;

Figs. 5, 6 and 7 are perspective views, respectively of the casing, the latch bolt and the lever handle;

Fig. 8 is a plan elevation of a modified form of the latch;

Fig. 9 is a similar view, showing the handle and latch bolt in retracting position;

Fig. 10 is a sectional view, taken along the line 10—10 of Fig. 8;

Fig. 11 is a bottom plan view;

Fig. 12 is a perspective view of a lever member employed therein; and

Fig. 13 is a sectional view thereof, taken along the line 13—13 of Fig. 12.

Similar reference characters indicate cor-

responding parts throughout the several figures of the drawings.

Referring to the drawings, and more particularly to Figs. 1 to 7 thereof, the latch, according to the embodiment shown therein, comprises a flanged sheet metal case 20, of vertically elongated shape, raised in spaced relation to the ends, as at 21, and provided in each of the end portions with holes 22 for engagement of attaching screws. A pair of apertured handle-supporting ears 23 and 24 are blanked from the casing, forming holes 25 and 26 therein, and are bent upwardly at right angles to the casing to provide pivot supports for the handle, said holes 25 and 26 being between said ears. A central aperture 27 is provided between said holes, for the pivotal support of a lever member, hereinafter more fully referred to. In the vertical side flanges of the case there are provided aligned slots 28 and 29 for the latch bolt, and in each of the end flanges prongs 30 are punched inwardly, and serve to retain the latch bolt spring, hereinafter referred to.

The handle 31, formed of sheet metal, is provided with right angularly bent side flanges 32 and 33, apertured as at 34 for engagement of a pintle, and at the forward lower edge portion of one of said flanges there is provided a downwardly extending finger 35. The handle is hingedly mounted upon the casing, between the ears 23 and 24, by means of a pintle 36, the lower edges of the flanges 32 and 33 resting upon the top of the casing and the finger 35 extending into the same through the hole 25, the holes 25 and 26 permitting swinging movement of the handle from the position shown in full lines (Fig. 4), with the flanges abutting the casing, to the dotted line position, with the forward transverse edge of the handle abutting the casing. A spring 37 coiled about the pintle 36 has one end engaged with the under forward surface of the handle, and its other end engaged in the hole 26, and yieldably retains the handle in its normal position.

The latch bolt comprises a flat rectangular strip of sheet metal 38, of relatively heavy gauge, beveled at its nose end, as at 39, and provided at its upper and lower edges with oppositely disposed aligned projecting lugs or fingers 40. The latch bolt is slidably engaged in the slots 28 and 29, with one of the

lugs 40 engaged with the finger 35 of the handle, and is yieldably held in projected position, and against said finger, by means of a coil spring 41 held within the casing by engagement of one of its end portions with an end flange of the casing beneath one of the prongs 30, and having its other end portion bent into a hole 42 provided in the latch bolt.

10 The latch bolt is of such dimensions that it may be readily assembled with the casing by hand, and for this purpose the distance from the nose end 39 to the rearward edges of the lugs 40 is slightly less than the interior width of the casing, so that by first engaging the tail end in the slot 29 to a point where the lugs 40 abut the casing, the nose end may be inserted in the slot 28, the spring 41 bringing the same into projected 20 position with one of the lugs abutting the finger 35 of the handle and thereby limiting the projection of the bolt.

Fig. 4 clearly illustrates the operation of the latch, the latch bolt adapted to engage 25 a suitable keeper 43 provided with a beveled strike portion 44 adapted as the door is closed to press the bolt inwardly to a point where it enters beneath the keeper. During the pressing in of the latch bolt by the 30 strike, the handle is held against movement by its spring 37, so that the bolt has a free, easy, and relatively quiet movement, and the handle is prevented from rattling. The latch bolt is retracted by swinging the handle outwardly, as shown in dotted lines, this 35 movement being substantially in the direction of opening of the door, so that the latch handle also effectually serves as a handle for the door. In case the bolt is not fully projected when engaged with the keeper, due to 40 warping of the door, or other causes, the handle will at all times be held against looseness by the spring 37.

In Figs. 8 to 13 there is illustrated a 45 modified adaptation of the latch, in which the handle is arranged at right angles to the direction of movement of the latch bolt. For this purpose the ears 23 and 24 are blanked and bent from the casing at right 50 angles to their placement in the first form, the structure of the casing being otherwise the same, and the same blanking and forming tools being used. The handle does not engage directly with the latch bolt, as in the 55 first form, but operates through an intermediate lever member 45. As shown in Figs. 12 and 13, this member is formed from sheet metal, and has a pivot boss 46 pressed therefrom at one side and a latch-bolt-engaging boss 47 pressed therefrom at the other side. The lever member is mounted in the latch by engaging its boss 46 in the center hole 27 of the casing, the boss 47 engaging one of the lugs 40 of the latch bolt. 60

65 The finger 35 of the handle is shorter than in

the first form, and engages a camming portion 48 of the lever member, the outward swinging of the handle, as shown in Fig. 9, causing the lever member to be rotated, and through it retracting the bolt.

70 In order to provide a latch of this type, wherein the bolt is disposed in the opposite direction, the finger 35 of the handle is provided on the other flange thereof, and the position of the lever member 45 is reversed, the booses being provided for this purpose of the opposed sides, that is, with the member as shown in Fig. 12, the boss 46 will project at the under side and the boss 47 will project at the upper side. The latch bolt and its spring are merely reversed in the casing, the provision of the lugs 40 at each longitudinal edge, and the symmetrical form of the casing, permitting this, without any change in their construction.

75 The latch, according to our invention, is of very simple and inexpensive construction, is reliable in operation, and by reason of its formation from sheet metal may by the mere transportation of the handle supports be 80 adapted for either horizontally or vertically disposed handles. The structure shown in Figs. 8 to 13 comprehends, with practically no additional tool expense, production of right or left hand door latches 85 of the vertical handle type shown therein, or of the horizontal handle type shown in Figs. 1 to 7.

90 We have illustrated and described preferred and satisfactory embodiments of our 100 invention, but it will be obvious that changes may be made therein, within the spirit and scope thereof, as defined in the appended claims.

Having thus described our invention, what 105 we claim and desire to secure by Letters Patent is:—

1. In a latch, a flanged casing having a pair of handle supports stamped and bent therefrom and providing an open portion between said supports, a handle supporting pin extending transversely between said supports, said flange having opposed latch bolt receiving slots, a latch bolt slidably engaged in said slots, a spring within said casing 110 adapted to normally project said bolt, a lever 115 said pin and including a top portion, side handle mounted between said supports upon flange portions and a latch bolt actuating portion extended into the casing through said open portion, said side flange portions, adapted to normally abut the upper side of said casing at one side of said open portion, and a spring coiled about said pin and having an end engaged with the top portion of 120 said handle and adapted to yieldably hold the same in its normal position independently of the latch bolt.

125 2. In a latch, a sheet metal flanged casing having a pair of handle supports stamped 130

and bent therefrom and providing an open portion between said supports, said flange having opposed latch bolt receiving slots, a latch bolt slidably engaged in said slots, a sheet metal lever handle having side flanges bent therefrom engaged and pivotally mounted between said supports and including a bolt actuating extension on one of said flanges extended into the casing through said open portion.

3. In a latch, a flanged casing having a pair of handle supports stamped and bent therefrom and providing an open portion between said supports, said flange having opposed latch bolt receiving slots, a flat sheet metal latch bolt slidably engaged in said slots including a projecting lug portion, a lever handle mounted between said supports and including a latch bolt actuating portion extended into the casing through said open portion.

4. In a latch, a flanged casing having a pair of handle supports stamped and bent therefrom and providing an open portion between said supports, said flange having opposed latch bolt receiving slots, a flat sheet metal latch bolt slidably engaged in said slots including transversely aligned projecting lug portions at each longitudinal edge, and a lever handle mounted between said supports and including a latch bolt actuating portion extended into the casing through said open portion.

5. In a latch, a flanged casing having a pair of handle supports stamped and bent therefrom and providing an open portion between said supports, said flange having opposed latch bolt receiving slots, a latch

bolt slidably engaged in said slots in spaced relation to the top of the casing, a lever handle mounted between said supports and including a latch bolt actuating portion extended into the casing through said open portion, and a rotary member pivotally mounted within the casing between the same and said bolt for rotation in a plane parallel to the movement of the bolt, engaged respectively with said latch bolt actuating portion of the handle and the bolt, and adapted upon actuation of the handle to retract the bolt.

6. In a latch, a flanged casing having a pair of handle supports stamped and bent therefrom and providing an open portion between said supports, said flange having opposed latch bolt receiving slots, a latch bolt slidably engaged in said slots in spaced relation to the top of the casing, a lever handle mounted between said supports and including a latch bolt actuating portion extended into the casing through said open portion, and a sheet metal rotary member having a pivot boss and a latch bolt engaging boss respectively stamped therefrom at opposite sides, pivotally mounted within the casing between the same and said bolt for rotation in a plane parallel to the movement of the bolt, engaged respectively with said latch bolt actuating portion of the handle and the bolt, and adapted upon actuation of the handle to retract the bolt.

Signed at Bridgeport, county of Fairfield, and State of Connecticut, this 4th day of June, 1926.
